UNITED STATES PATENT OFFICE.

JOHN H. WOODALL, OF WOODLAND, GEORGIA.

MACHINE FOR SEALING CRATE CUSHIONS.

Application filed September 16, 1926. Serial No. 135,903.

This invention relates to a machine for sealing crate cushions of the character shown in my application No. 108,905, filed May 13, 1926, and has for its object the economic and rapid automatic sealing of the ends of said cushions.

Another object of the invention is to attach the seal to the cushions uniformly without injuring the cushions during the handling of the same.

With these and other objects in view, I will now describe my invention in connection with the accompanying drawings in which:

Figure 1 is a plan view of my machine.

Fig. 2 is a side view.

Fig. 3 is a view showing one end of the cushion as it comes into proximity with the tape that is to be glued to the end of the cushion.

Fig. 4 is a view of the cushion in its further travel through the tape attaching device.

Fig. 5 is a view showing a further advance of the cushion and tape.

Fig. 6 is a view showing the position of parts as the tape is being pressed into close contact with the cushion.

Fig. 7 is a view of the tape folder.

Fig. 8 is a sectional view of the folder on the line 8—8 of Fig. 7.

Fig. 9 is a view of the folder on the line 9—9 of Fig. 7, and

Fig. 10 is a view on the line 10—10 of Fig. 7.

1—1' are rolls of tape of convenient width, sufficient to overlap the open ends of the cushions. The tape is passed over suitable rollers 2—2' and from the rollers the tape passes through trough-like tanks 3—3' containing

a suitable liquid. The tapes are given a half turn by suitable rollers 4—4' in order to apply the glue or paste to one side of the tape or if the tape is gummed, to moisten the tape.

The tapes 5—5' are thence passed to the entrance ends 6—6' of the folders 7. These folders, as best shown in Figures 7 and 8, have in their side faces a groove extending from end to end of the folder. This groove 8 starting from near the left-hand end as shown in Figs. 7 and 8 becomes deeper and narrower

towards the right hand end as shown in Fig. 7 to gradually fold the tape in the shape shown in Fig. 5.

I may have a metallic lining 10 in the bottom of the groove 8 although this is not necessary and can be left out if desired.

The machine frame may comprise a base 11 (Fig. 2) uprights 12 and supporting horizontal beams 13. 15 is the drive wheel which may be run from any suitable source of power. I conveniently provide reducing gears 16—17—18 and connect the gear 18 by a sprocket chain 9 to a gear 20 on a shaft 21 on which is a roller somewhat longer than the cushions to be sealed. A second roller 23 is 60 suitably supported in a frame 24 above the first mentioned roller, the second roller being adjustably held to the first roller by a spring 25 conveniently bolted with an adjusting screw 26. The second roller 23 is 65 conveniently hollowed out sufficiently to compensate for the thickness of a belt 28 and the cushion as best shown in Fig. 6, leaving at each end of the roller, portions 29—29' having a greater diameter than the portion of 70 the roller between the parts 29 and 29' as best shown in Fig. 1. The parts 29—29' of the roller 23 preferably contact with the similarly shaped lower roller around which runs the belt 30, extending beyond the end of the 75 belt 28. The parts 29—29' of the upper roller 23 and the like parts of the similarly shaped lower roller constitute coacting pressure rolls at the extremities of said rollers. Between the lower flight of the belt 28 and the upper flight of the belt 30, the cushions are inserted and carried by the belts 30 and 28 to the right as shown in Figs. 1 and 2 with the open ends of the cushions in proximity to the tapes as shown best in Fig. 3. As the 80 cushions 32 are moved to the right, a previously inserted cushion to which the tapes have been attached, pulls the tapes 5 and 5' over the ends 6 and 6' of the folder 7 and the sides of the tape are gradually bent over the 85 open ends of the cushion as shown in Figs. 3, 4 and 5. After this operation the tapes pass between the pressure rolls 29 and 29' of the upper roller and the similar pressure rolls of the lower roller and the tapes and end 90 portions are pressed together as shown in Fig. 6, the cushions passing further on to a platform 36 where an attendant severs the portion of the tape between successive cushions 32. The coacting pressure rolls of the 95 two rollers press on the tapes with sufficient pressure to cause the glue or paste on the top to thoroughly adhere to the ends of the cushion and thus seal the same. The reduced intermediate parts of the two coacting 100 discharge rollers, the roller 23 and the one immediately below, permit the passage of 105 110

the body part of the cushion without undue compression of the filling in the cushions.

To operate the machine, the attendant stands at the left as shown in Figs. 1 and 2 and feeds the cushions between the bands 5 and 28. Of course with the first cushion that is passed through the machine, the tape must be first manually attached to said first cushion, or the tapes are pulled through the 10 folders and placed between the pressure rolls of the rollers, the successive cushions being glued to the tape when the pressure rolls presses the parts together as shown in Fig. 6, thereafter pull the tapes 5 and 5' along with 15 the cushions as they are successively fed to the machine, the tapes being gradually folded by the folder 7 to each cushion, as it passes through the machine, and the attendant cuts the tapes between the cushions at the right 20 hand end of the machine after the cushions are deposited on the platform 36.

The machine may be run at any convenient speed and has been found quite efficient in securely and evenly applying the tapes and 25 sealing the same.

Having described my machine and its mode of operation, what I claim as new is:

1. In a machine for sealing the ends of 30 cushions, the combination of a conveyer for moving cushions successively through the machine, with means for folding tape over the ends of cushions carried by the conveyer comprising an elongated folder extending along the travel of each of the cushion ends and 35 having in its inner face a groove to engage the ends of passing cushions, said groove being wide and shallow at its receiving end and gradually decreasing in width and increasing in depth toward its discharge end, 40 means for feeding tape through the groove to be folded over the ends of the passing cushions, and coacting pressure rolls mounted in tracking relation to the discharge end of the groove of each folder with at least one of 45 the coacting rolls having a width approximately of the same width as the taped end of the cushion, said coacting rolls operating to compress the taped end of the cushion passing between said coacting rolls.

2. In a machine for sealing the ends of 50 cushions, the combination of a conveyer for moving cushions successively through the machine, with folders extending along the travel of the ends of cushions carried by the conveyer to fold tape over the ends of the passing 55 cushions, coacting pressure rollers at the delivery end of the conveyer operating to engage the discharging cushions with at least one of said rollers having its intermediate 60 part of reduced diameter to compress lightly the body part of the engaged cushion and said roller having its extremities of enlarged diameter to form pressure rolls located in tracking relation to the folders, said pressure rolls 65 coacting with the ends of the adjacent pres-

sure roller to compress the taped ends of the cushions discharging from the folders and also operating to draw tape through the folders, and means for supplying tape to the folders.

3. In a machine for sealing the ends of 70 cushions, the combination of upper and lower rollers carrying upper and lower belts having coacting flights to engage cushions therebetween to move the cushions 75 successively through the machine, folders extending along the belt flights to fold tape over the cushion ends projecting from said flights, the rollers at the delivery end of the belts forming compression rollers to apply 80 pressure to the discharging cushions, at least one of said compression rollers having its intermediate part of reduced diameter to provide an intervening space between the compression rollers to receive the bulk of the 85 discharging cushion and to apply light pressure to the body part of the discharging cushions and said compression roller of reduced diameter also having its extremities of enlarged 90 diameter to form rolls in tracked relation to the discharge ends of the folders, said rolls coacting with the ends of the adjacent compression roller to apply heavy pressure to the taped ends of the discharging cushions, and means for supplying tape to the receiving 95 ends of the folders to be drawn through the folders by the pressure rolls and coacting compression roller engaging the taped ends of the cushions.

4. In a machine for sealing the ends of 100 cushions, the combination of upper and lower rollers carrying upper and lower belts having coacting flights to engage cushions therebetween to move the cushions successively 105 through the machine, elongated folders extending along the coacting belt flights between the rollers supporting the belts, each of said folders having in its inner face a groove to engage the ends of cushions projecting beyond the adjacent edges of the coacting belt flights, said groove being wide and shallow at its receiving end and gradually decreasing in width and increasing in depth toward its delivery end, said folders operating 110 to fold tape over the cushion ends projecting beyond the adjacent edges of the coacting belt flights, the rollers at the delivery end of the belts forming compression rollers to apply pressure to the discharging cushions, said compression rollers having their 115 intermediate parts of reduced diameter to receive bights of their respective belts and also to provide an intervening space between the rollers to receive the bulk of the discharging 120 cushions and to apply light pressure to the body part of the discharging cushions and said compression rollers also having their extremities of enlarged diameter to form pressure 125 rolls in tracked relation to the discharge ends of the grooves in said folders, said pres- 130

sure rolls on each side coating with each other to apply heavy pressure to the taped ends of the discharging cushions, and means for supplying tape to the receiving ends of the folders to be drawn through the grooves thereof by the coating pressure rolls engaging the taped ends of the cushions.

5. In a machine for sealing the ends of cushions, the combination of a conveyer for feeding cushions successively through the machine, with a folder for folding tape over the ends of cushions carried by the conveyer, said folder comprising an elongated member having a groove extending along the travel 10 of the ends of the cushions carried by the conveyer, said groove being wide and shallow at

its receiving end and gradually decreasing in width and increasing in depth toward its discharge end, a lining plate shaped to fit the groove and having its longitudinal edges 20 turned inward to form flanges to engage the side parts of tape fed through the groove to guide the tape onto the ends of cushions passing between said flanges, means for feeding tape through the groove in said folder, and coating pressure rolls mounted at the discharge end of the folder to compress the 25 taped edges of the cushions as said edges leave the folder.

In testimony whereof I affix my signature.

JOHN H. WOODALL.
